UNITED STATES PATENT OFFICE

2,027,313

REFRIGERATOR

Donald H. Gaston, Fort Wayne, Ind., assignor to
 General Electric Company, a corporation of
 New York

Application June 14, 1935, Serial No. 26,569

10 Claims. (Cl. 62—116)

5 My invention relates to refrigerators, and more particularly to an arrangement for minimizing the transfer of heat from an accumulator or receiver located adjacent the top of a refrigerator cooling compartment to the compartment.

10 Many types of refrigerators and particularly those designed for domestic use are provided with a cabinet having a cooling compartment therein located just below the top wall of the cabinet.

15 The cooling compartment is ordinarily cooled by a refrigerant evaporator in which liquid refrigerant is vaporized by the transfer of heat thereto from the contents of the cooling compartment.

20 The liquid refrigerant is frequently supplied to the evaporator, especially when the latter is of the flooded type, from an accumulator or receiver located above the level of the evaporator. In such case, difficulty has been encountered in providing a suitable location for the accumulator which contains relatively hot liquid refrigerant since the proximity of the top of the cooling compartment to the top of the cabinet limits the available space therebetween.

25 It is an object of my invention to provide a refrigerator of the type described having a cooling compartment, a liquid refrigerant accumulator or receiver located adjacent the top of the compartment and an improved and simplified arrangement for minimizing the flow of heat 30 from the accumulator to the interior of the compartment.

35 Further objects and advantages of my invention will become apparent as the following description proceeds and the features of novelty which characterize my invention will be pointed out with particularity in the claims annexed to and forming a part of this specification.

40 For a better understanding of my invention, reference may be had to the accompanying drawing in which Fig. 1 is a side elevation, partly in section, of the upper portion of a refrigerator embodying my invention; Fig. 2 is a fragmentary plan view of the top plate of the inner liner of the refrigerator shown in Fig. 1, the cover and 45 insulation being removed; Fig. 3 is a perspective view of a rubber boot which surrounds the float valve chamber of the refrigerator shown in Fig. 1; Fig. 4 is a perspective view of a portion of the top plate of the liner of the refrigerator shown 50 in Fig. 1; and Fig. 5 is a perspective view of a portion of a modified form of top plate and flexible heat insulating casing, which may be used in the refrigerator shown in Fig. 1.

55 Referring to the drawing, in Fig. 1 I have shown the upper portion of a refrigerator of the domes-

tic type provided with a cabinet having outer walls which are formed by a rectangular open top steel shell 10. An inner rectangular open top steel shell 11 forms the side walls of a cooling compartment 12. The inner and outer side walls 10 and 11 thus formed are separated by heat insulation 13 and the front walls thereof are provided with registering apertures forming a door opening which is closed by a heat insulated door 14. The top wall of the cabinet is 10 formed by a rectangular sheet metal top plate 15 and a rectangular sheet metal cover 16 which are separated by heat insulation 17. The top plate 15 rests on a peripheral inturned flange 18 which extends about the opening formed in the 15 top of the inner liner 11. The edge of the insulation 13 surrounding the opening in the top of the inner liner 11 is covered by a band of cloth 13a. The cover 16 rests on a rectangular rubber gasket 19 which extends about the top 20 of an upstanding peripheral flange 20 formed at the upper edge of the outer shell 10. A downwardly extending peripheral flange 21 extends entirely about the edge of the cover 16 and the front and rear portions thereof are provided with 25 inwardly extending portions 22 and 23 which rest on the horizontal top portions 24 and 25 respectively of the outer shell 10. The inwardly extending portion 22 of the cover 16 is pressed against the top portion 24 of the shell 10 by a 30 resilient spring clip 26, the rear end of which is secured by a bolt 27 to the top portion 24 of the shell 10. The rear portion of the cover 16 is secured to the cabinet by a strap 28, the upper end of which is secured to the rear portion 35 of the flange 21 on the cover 16 by a screw 29 and the lower end of which is secured to the rear wall of the shell 10 by a screw 30.

35 The compartment 12 is cooled by a sheet metal evaporator 31 of the flooded type which is formed 40 of inner and outer sheets of metal 32 and 33 respectively, the outer sheet 33 being provided with a series of indentations 34 or corrugations therein which provide refrigerant circulatory passages 35 extending about the walls of the evaporator. The 45 refrigerant circulatory passages 35 communicate with a longitudinal header 36 having a cylindrical cross section formed by complementary indentations in the sheets 32 and 33, the passages 35 communicating with the header 36 below the level 50 of the liquid refrigerant therein. The upper edges of the sheets 32 and 33 are bent inwardly to form a flange 32a which is secured to the top liner 15 by bolts 33a, thus supporting the evaporator 31 on the lower side of the top liner 15.

Liquid refrigerant is supplied to the evaporator 31 from a refrigerant accumulator or receiver which in the illustrative form of my invention is a float valve casing 37. The float valve casing 37 is supported in an aperture 38, formed in the rear edge of the top liner 15, by straps 39 and 40 which extend about the float valve casing 37 and are secured in firm engagement therewith by machine screws 41 and 42. As shown in Fig. 2, the strap 39 is somewhat longer than the strap 40 and the ends thereof are provided with horizontal brackets 43 and 44 which are secured by bolts 45 and 46 respectively to the top plate 15.

The transfer of heat from the relatively hot liquid refrigerant accumulated in the float valve casing 37 is minimized by a flexible heat insulating shield extending about the portion of the casing 37 which projects into the compartment 12. A molded flexible rubber boot 47 forms the heat insulating shield. The rubber boot is provided with a cup-shaped open top body portion 48, the interior diameter of which is slightly larger than the exterior diameter of the casing 37. An opening 49 is formed in the bottom of the casing 37 through which the outlet 50 of the casing 37 extends. A peripheral integral flange 51 extends about the top of the boot 47, the rear portion 52 of the flange 51 being offset downwardly with respect to the front portion thereof in order to conform with the offset configuration of the rear portion 53 of the top liner 15, shown in Fig. 4. The flange 51 on the boot 47 is provided with a groove 54 therein extending about the same which receives the edge of the top liner 15 about the aperture 38 therein. The rear portion 52 of the flange 51 is secured to the rear portion of the flange 18 formed on the rear wall of the inner liner 11 by machine screws extending through holes 55 in the boot 47 and registering holes formed in the flange 18. The boot 47 thus forms a good seal about the edges of the aperture 38 and the top liner 15 and the adjacent portion of the top of the inner liner 11 effectually preventing the leakage of warm air therethrough. The sides of the hole 49 formed in the bottom of the boot 47 closely engage the lower extension 50 formed on the float valve casing 37 in order to prevent the leakage of warm air into the compartment 12. Since rubber is a comparatively poor conductor of heat, the transfer of heat from the relatively hot liquid refrigerant contained in the float valve casing 37 to the contents of the cooling compartment 12 is minimized by the boot 47. The boot may be readily molded from rubber, or other flexible material, and inserted in place during the assembly of the refrigerating machine. Its use obviates the necessity of providing a more complicated form of sheet metal top plate to conform to the bottom of the float valve casing 37 and provision of suitable insulation surrounding the same, or a construction in which the top plate and cover of the cabinet are spaced apart a greater distance in order to provide space for the float valve chamber 37.

In Fig. 5, I have shown a modified form of top plate which may be substituted for the top plate 15 shown in Fig. 1. The top plate shown in Fig. 5 has the same exterior dimensions as the top liner 15, but consists of two separable sheet metal plates 56 and 57 having adjacent upwardly extending flanges 58 and 59 respectively which are secured together by suitable bolts 60. Complementary recesses 61 and 62 are formed in the adjacent edges of the plates 56 and 57 forming an aperture adapted to receive an open top cup

shaped boot 63 made of rubber or similar flexible insulating material. The rubber boot 63 is provided with an offset portion 64 adapted to receive an inlet connection for the float valve casing which is fitted in the boot. A peripheral flange 65 extends about the upper edge of the boot 63 and is provided with a groove 66 extending thereabout. The adjacent edges of the recesses 61 and 62 in the plates 56 and 57, respectively, are placed in the groove 66. It will be seen that the plates 56 and 57 may be removed from the top of the cabinet after disengaging the bolts 60 upon moving the plates laterally out of engagement with the boots 63 without disturbing the latter and the float valve casing contained therein. The ends of the flanges 58 and 59 are spaced from the edges of the recesses 61 and 62 to provide space for the flange 65.

In the operation of the machine described above compressed gaseous refrigerant is supplied to a natural draft air cooled condenser 66 from a suitable refrigerant compressor or the like which may be located in a machinery compartment adjacent the bottom of the cabinet. The condenser 66 is supported on the exterior side of the rear wall 25 of the cabinet by a bracket 67 which is secured to the rear wall of the shell 10 by a bolt 68. The refrigerant liquefied in the condenser 66 is forced into the float valve chamber 37 through a conduit 69 under the pressure exerted thereon by the refrigerant compressor. The liquid refrigerant accumulated in the float valve chamber 37 flows therefrom through the outlet extension 50 and supply conduit 70 to the refrigerant circulatory passages 35 of the evaporator 31. The admission 35 of liquid refrigerant to the evaporator 31 is controlled by the float valve located in the float valve chamber 37. The header 36 of the evaporator 31 is maintained about half full of liquid refrigerant, the circulatory passages 35 of the evaporator 31 thus being maintained flooded with liquid refrigerant. The liquid refrigerant contained in the evaporator 31 is vaporized by the absorption of heat from the contents of the cooling compartment 12 and the vaporized refrigerant is collected above the level of the liquid refrigerant in the header 36. The vaporized refrigerant thus accumulated in the header 36 is returned to the refrigerant compressor through a conduit 71 which communicates with the header 36 above the level of the liquid refrigerant therein. The conduit 71 extends about the float valve chamber 37 in heat exchange relationship therewith in order that the cold vaporized refrigerant in the conduit 71 may be utilized to cool the relatively hot liquid refrigerant in the float valve casing 37. It will be noted that the conduits 69 and 71 extend through a slot 72 formed in the rear portion of the flange 20 on the shell 10, a rubber gasket 73 being positioned on the portions of the conduits 69 and 71 adjacent the sides of the slot 72 in order to protect the same from damage. The portions of the conduits 69 and 71 adjacent the top of the rear wall of the cabinet are covered by a molded rubber sleeve 74 which protects the portions of the conduit extending through a slot 75 formed in the rear portion of the flange 21 on the cover 16.

While I have shown a particular embodiment of my invention in connection with a refrigerating machine of the household type, I do not desire my invention to be limited to the particular construction shown and described and I intend, in the appended claims, to cover all modifications within the spirit and scope of my invention.

What I claim as new and desire to secure by Letters Patent of the United States, is:

1. A refrigerator including a heat insulated cooling compartment having an aperture in the top wall thereof, means including an evaporator mounted in said compartment for abstracting heat therefrom, means including a refrigerant accumulator for supplying liquid refrigerant to said evaporator, said accumulator being located in said aperture and having the lower portion thereof extending into said compartment, and means including a shield of flexible heat insulating material surrounding said lower portion of said accumulator extending into said compartment for minimizing the transfer of heat from the liquid refrigerant in said accumulator to said compartment.
2. A refrigerator including a heat insulated cooling compartment having a sheet metal top plate forming the interior top wall thereof, said top plate having an aperture therein adjacent the rear edge thereof, means including an evaporator supported on the lower side of said top plate for abstracting heat from said cooling compartment, means including a refrigerant accumulator for supplying liquid refrigerant to said evaporator, said accumulator being located in said aperture and having the lower portion thereof extending into said compartment, and means including a shield of flexible heat insulating material surrounding said lower portion of said accumulator extending into said compartment for minimizing the transfer of heat from the liquid refrigerant in said accumulator to said compartment.
3. A refrigerator including a heat insulated cooling compartment having an aperture in the top wall thereof, means including an evaporator mounted in said compartment for abstracting heat therefrom, means including a float valve and refrigerant accumulating casing therefor for maintaining said evaporator flooded with liquid refrigerant, said casing being located in said aperture and having the lower portion thereof extending into said compartment, and means including a shield of flexible heat insulating material surrounding said lower portion of said casing extending into said compartment for minimizing the transfer of heat from the liquid refrigerant in said casing to said compartment.
4. A refrigerator including a heat insulated cooling compartment having a sheet metal top plate forming the interior top wall thereof, said top plate having an aperture therein adjacent the rear edge thereof, means including an evaporator supported on the lower side of said top plate for abstracting heat from said cooling compartment, means including a float valve and refrigerant accumulating casing therefor for maintaining said evaporator flooded with liquid refrigerant, said casing being located in said aperture and having the lower portion thereof extending into said compartment, and means including a shield of flexible heat insulating material surrounding said lower portion of said casing for minimizing the transfer of heat from the liquid refrigerant in said casing to said compartment.
5. A refrigerator including a heat insulated cooling compartment having an aperture in the top wall thereof, means including an evaporator mounted in said compartment for abstracting heat therefrom, means including a refrigerant accumulator for supplying liquid refrigerant to said evaporator, said accumulator being located in said aperture and having the lower portion thereof extending into said compartment, and means including a moldable flexible rubber boot surrounding said lower portion of said accumulator for minimizing the transfer of heat from the liquid refrigerant in said accumulator to the contents of said compartment.
6. A refrigerator including a heat insulated cooling compartment having a sheet metal top plate forming the interior top wall thereof, said top plate having an aperture therein adjacent the rear edge thereof, means including an evaporator supported on the lower side of said top plate for abstracting heat from said compartment, means including a refrigerant accumulator for supplying liquid refrigerant to said evaporator, said accumulator being located in said aperture and having the lower portion thereof extending into said compartment, and means including a moldable flexible rubber boot surrounding said lower portion of said accumulator and secured to the edges of said top plate surrounding said aperture therein for minimizing the transfer of heat from the liquid refrigerant in said accumulator to said compartment, said boot being spaced from said accumulator.
7. A refrigerator including a heat insulated cooling compartment having a sheet metal top plate forming the interior top wall thereof, said top plate having an aperture therein adjacent the rear edge thereof, means including an evaporator supported on the lower side of said top plate for abstracting heat from said cooling compartment, means including a refrigerant accumulator for supplying liquid refrigerant to said evaporator, said accumulator being located in said aperture and having the lower portion thereof extending into said compartment, and means including a moldable flexible cup-shaped rubber boot surrounding the lower portion of said accumulator for minimizing the transfer of heat from the liquid refrigerant in said accumulator to the contents of said compartment, said boot being provided with a peripheral flange surrounding the upper edge thereof, said flange having a groove therein adapted to receive the adjacent edge of said aperture in said top plate.
8. A refrigerator including a heat insulated cooling compartment having a sheet metal top plate forming the interior top wall thereof, said top plate having a recess in the rear edge thereof, means including an evaporator supported on the lower side of said top plate for abstracting heat from said cooling compartment, means including a refrigerant accumulator for supplying liquid refrigerant to said evaporator, said accumulator being located in said recess and having the lower portion thereof extending into said compartment, means including a moldable flexible cup-shaped rubber boot surrounding said lower portion of said accumulator and spaced therefrom for minimizing the transfer of heat from the liquid refrigerant in said accumulator to said compartment, said boot being provided with a flange extending about the upper edge thereof and having a groove therein adapted to receive the adjacent edge of said recess in said top plate, and means for securing the rear portion of said flange on said boot to the adjacent portion of the rear wall of said compartment.
9. A refrigerator including a heat insulated cooling compartment, a pair of sheet metal plates forming the interior top wall of said compartment, said plates being provided with comple-

mentary recesses therein, means including an evaporator mounted in said compartment for abstracting heat therefrom, means including a refrigerant accumulator for supplying liquid refrigerant to said evaporator, said accumulator being located in said complementary recesses and having the lower portion thereof extending into said compartment, and means including a shield of flexible heat insulating material surrounding said lower portion of said accumulator extending into said compartment for minimizing the transfer of heat from the liquid refrigerant in said accumulator to said compartment.

10. A refrigerator including a heat insulated cooling compartment, a pair of sheet metal plates forming the interior top wall of said compartment, said plates being provided with com-

plementary recesses in the adjacent edges thereof, means including an evaporator mounted in said compartment for abstracting heat therefrom, means including a refrigerant accumulator for supplying liquid refrigerant to said evaporator, said accumulator being located in said complementary recesses and having the lower portion thereof extending into said compartment, and means including a molded flexible rubber boot surrounding the lower portion of said accumulator and engaging the adjacent edges of said complementary recesses for minimizing the transfer of heat from the liquid refrigerant in said accumulator to said compartment.

DONALD H. GASTON.
